Primary Examiner — Mitchell I. Siegel(74) *Attorney, Agent, or Firm* — Bridgeway IP Law Group, PLLC; Sang Ho Lee; Hyun Woo Shin(57) **CLAIM**

I claim the ornamental design for a putter shaft, as shown and described.

DESCRIPTION

FIG. 1 is a perspective view of a putter shaft, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown on the drawings form no part of the claimed design.

1 Claim, 6 Drawing Sheets---
